UNITED STATES PATENT OFFICE.

GEORGE GRUBER, OF DETROIT, MICHIGAN.

BRUSH.

SPECIFICATION forming part of Letters Patent No. 247,247, dated September 20, 1881.

Application filed June 17, 1881. (No model.)

To all whom it may concern:

Be it known that I, GEORGE GRUBER, of Detroit, in the county of Wayne and State of Michigan, have invented an Improvement in 5 Brushes, of which the following is a specification.

The nature of this invention relates to new and useful improvements in the manufacture of brushes; and the invention consists in the 10 process of manufacture and the peculiar construction and arrangement of parts, as more fully hereinafter described, and then pointed out in the claims.

Figure 1 is a perspective view of my press ready for operation. Fig. 2 is a vertical cross-section of the same in operation, and showing the manner in which the brush-head is engaged to the ends of the bristles. Fig. 3 is a 15 perspective of my improved brush-head. Fig. 20 Fig. 4 is a longitudinal vertical central section of my improved brush.

In the accompanying drawings, which form a part of this specification, A represents the bed of my press, provided with the end stops, 25 B, and the rear stop, C, the end stops limiting the length of the brush itself, while the stop C limits the projection of the bristles from the head.

D is the platen of my press, provided with 30 a flange, E, upon its under side, the length of said flange being equal to the distance between the stops B, but in thickness less than the thickness of the stops B; and the two parts A, D are provided with dowels a and 35 holes b, which engage when the parts are put together.

F represents the bristles of which the brush is formed, which are laid upon the bed A with their ends against the inner face of the stop 40 C, their stubs or outer ends projecting, as shown in Fig. 2, beyond the front face of the press. The space between the stops B being loosely filled with bristles, as described, the platen D is engaged by means of the dowels 45 and holes, and any power appropriate or convenient is applied to compress the bristles between the flange E and the upper face of the bed, leaving the stubs projecting, as shown in Fig. 2.

G is the head of the brush, made of any 50 suitable material, and cut longitudinally with a circular groove, c, terminating in a rectangular groove, d, at the lower edge of the head, said grooves opening only at one end of the brush-head. The bristles being pressed in position as described, the head is engaged with the projecting stubs of the bristles, as shown in Fig. 2, one end of the grooves being stopped. After the head has been engaged in this manner, cement which will not be affected by water is poured through the vertical hole e, which is bored from the top of the head down to the channel or groove, until the entire space in said groove not occupied by the projecting 55 ends of the stubs of the said bristles is filled. 60 Care should be taken, however, to stop the other end of the groove before pouring in the cement. When the cement sets, which it will do very rapidly, the bristles will be held therein with as much certainty and with as little 65 danger of displacement as when sewed in in the ordinary manner.

I am aware that brush-heads have been made with grooves for holding sponges, and also for holding bristles held in metal frames, 75 said grooves being open at both ends of the heads; and I am also aware that it is not new to make brush-knots by pressing bunches of bristles previously coated with cement into suitable formers; and therefore I do not broadly claim either of said constructions.

What I claim as my invention is—

1. The process herein described of manufacturing brushes, consisting in compressing a suitable quantity of bristles at a point near 85 the stub ends in a suitable clamp, then sliding the ends projecting from the clamp into a brush-head having an open groove of large internal diameter, then removing the clamp, and finally securing the bristles in the head by filling the groove in the latter not already occupied with the bristles with a suitable cement, 90 substantially as specified.

2. The brush-head G, provided with a large groove, c, and a slot, d, of smaller size opening from said groove, the groove and slot being open at one end of the head only, in combination with the bristles F, compressed at a 95

point near their stub ends, and a suitable cement for fastening the bristles in place, substantially as specified.

3. The brush-head G, provided with a large 5 groove, c, and a slot, d, of smaller size opening from said groove, the groove and slot being open at one end of the head only, in combination with the bristles F, compressed at a point near their stub ends, and a plug for closing the open end of the groove and slot, substantially as specified.

4. As a new article of manufacture, the brush-head G, provided with a hole, e, a groove, c, and a slot, d, of smaller size than the groove c, the groove and slot being open at one end 15 of the block or head only, and the hole e opening into the groove c, substantially as described.

GEO. GRUBER.
